UNITED STATES PATENT OFFICE.

WILLIAM E. SUDLOW, OF WASHINGTON, AND HENRY J. WHITE, OF AUGUSTA, GEORGIA.

SMOKE-CONSUMING FURNACE.

984,979.

Specification of Letters Patent. Patented Feb. 21, 1911.

Application filed October 5, 1909. Serial No. 521,087.

To all whom it may concern:

Be it known that we, WILLIAM E. SUDLOW, a British subject, and HENRY J. WHITE, a citizen of the United States, residing, WILLIAM E. SUDLOW, at Washington, Georgia, and HENRY J. WHITE at Augusta, Georgia, have invented new and useful Improvements in Smoke-Consuming Furnaces, of which the following is a specification.

10 This invention relates to smoke consuming furnaces, the object of the invention being to provide a construction of furnace whereby a more perfect combustion of fuel and elimination of carbon, or as it is commonly termed, smoke is effected, by causing the unconsumed gases after leaving the fire bed to be directed into contact with highly heated surfaces of fire-resisting material before allowing the same to come in contact 15 with any portion of the boiler, whereby the gases are thoroughly heated and caused to ignite, thereby eliminating the smoke nuisance, economizing in fuel and also greatly increasing the life and durability of the 20 boiler.

25 With the above and other objects in view, the nature of which will more fully appear as the description proceeds, the invention consists in the novel construction combination and arrangement of parts as herein fully described, illustrated and claimed.

30 In the accompanying drawings:—Figure 1 is a central vertical longitudinal section through a smoke consuming furnace embodying the present invention. Fig. 2 is a plan view thereof, partly in horizontal section. Fig. 3 is a front elevation of the furnace, partly in section.

35 The furnace is constructed out of fire brick or other suitable fire-resisting material and comprises the side walls 1, front wall 2, rear wall 3 and in the construction shown in Fig. 1, the furnace also comprises a bridge wall 4 located at the usual point 40 and forming the back wall of the fire box.

45 5 designates the furnace grate beneath which is the ash pit 6.

7 designates a plurality of fuel openings and 8 other openings leading to the ash pit. 50 Extending back from the top of the bridge wall 4 is an elevated floor 9 which reaches to the rear wall 10 of the furnace and is supported at intervals by additional walls 11. Extending over the floor 9 is an arch 12 or 55 in other words, a transversely curved wall which is arranged beneath the boiler 13 and

extends lengthwise of the boiler as shown in Fig. 1. In the preferred embodiment of the invention, an inverted arch or transversely curved wall 14 is interposed between the wall 12 and the bottom of the boiler, as best illustrated in Fig. 3, thereby forming an arcuate space 15 along which the thoroughly ignited products of combustion pass in their first contact with the shell of the boiler. 60 The walls 12 and 14 preferably meet or merge into each other, as shown at 16 in Fig. 3, whereby they mutually brace and support each other.

65 The two arches above described terminate 70 a sufficient distance in advance of the rear wall 10 to leave an opening 18 up through which the products of combustion pass in entering the arcuate space 15. Between the floor 9 and the arch 12 are baffle walls 19. These 75 walls extend vertically between the floor 9 and the arch 12 and project from the opposite side walls 1 inward part way across the space between the side walls, as indicated by dotted lines 19 in Fig. 2, thereby causing 80 the products of combustion to take an irregular course in passing for the first time lengthwise beneath the boiler, the arches 12 and 14 preventing the gases at such time from coming in contact with the boiler shell. 85 The bridge wall, as well as the floor 9 and the arches 12 and 14 and the baffle walls 19 soon become highly heated and as a result, by reason of the gases impinging against the 90 said highly heated surfaces, they are ignited 90 before passing through the space 18 and coming in contact with the boiler 13, as they move along the arcuate space 15.

95 Upon reaching the front end of the furnace, the products of combustion enter the front connection or chamber 20 and pass thence rearward through the flues of the boiler into the rear connection 21, the front of which is defined by the rear end of the boiler and the rear wall 10 of the furnace, 100 the area of this rear connection 21 being large in comparison with the area of the stack or the passages leading from the furnace to this chamber, it follows that any soot carried as a solid suspended in the moving gases will be deposited at this point 105 where the said gases will move at a much slower rate than at any other point of their travel from the furnace to the stack.

110 The rear connection or chamber 21 is provided at or near its center with a dividing baffle wall 22 reaching to the top of the

chamber 21 and terminating above the bottom thereof as shown in Fig. 1, causing the products of combustion after leaving the flues of the boiler to pass downward on one side of the wall 22 and then upward on the opposite side thereof between said wall and the rear inclosing wall 23 of the back chamber 21.

Within the chamber 21 there is arranged 10 a feed water pipe heater, comprising a number of vertical water tubes 24 connected at their upper and lower ends to horizontal pipes 25, the pipes 25 being in turn connected to headers 26 arranged at the top and 15 bottom of the heater, the lower header 26 being provided with a blow-off pipe 27 while the upper header 26 has leading from the opposite ends thereof, pipes 28 and 29 which communicate with a common feed water 20 pipe 30 that enters the boiler at 31 and is connected by an elbow 32 to a horizontally disposed distributor or spray pipe 33 having a number of perforations 34. This distributor or spray pipe 33 extends horizontally 25 within the boiler about two inches above the tubes or flues of the boiler so that it is always covered with water.

In addition to its function of supplying feed water to the boiler, the construction 30 above described provides for blowing off the boiler periodically as needed, the perforations 34 acting to draw the scum from the surface of the water and blow the same outward through the connections described.

35 designates a bottom blow off pipe for the boiler which passes up through the rear end wall 3 of the furnace and enters the boiler.

35^a designates a feed water pipe entering 40 the lower header 26 of the heater.

36 designates an outlet orifice for the products of combustion, in connection with which a suitable stack may be employed. The boiler may be supported in the masonry 45 in any convenient or usual manner and may be provided with side supporting lugs 37 for that purpose, although, any other means may be employed for suspending or supporting the boiler out of contact with the 50 heated fire-resisting surfaces. If desired, a door 38 may be provided in the front wall of the furnace to give access to the adjacent end of the boiler for cleaning and repairing. The boiler may also be provided with the 55 usual number of manholes 39.

By reference to Figs. 2 and 3, it will be observed that the side walls of the furnace are provided with fresh air passages 40 leading from the top downward and ending in elbows or ports 41 which lead into the ash pit beneath the grate, as shown in Figs. 1 and 3, the said passages being adapted to be closed by cut offs 42 shown in Fig. 3. The baffle walls 19 are also provided with air ducts 43 60 opening into the space between the floor 9

and arch 12 and supplied by the air passing down the side passages 40 above referred to.

The side walls, the arch or arches, the bridge wall and the projecting baffle wall, all being removed from the cooling influence 70 of the boiler itself may be intensely heated by the combustion of fuel in the furnace and as the temperature of the gases thrown off from the fuel changes, falling by reason of the opening of the furnace doors for the application of fresh fuel, or the cleaning of the fire, or rising when the combustion of the fuel is perfect, these structures will deliver heat to the passing gases when the gases are cooler than said structures or walls, and said 80 walls will absorb heat from the gases when the latter are hotter than the walls, resulting in more constant even temperature of the gases at the point where they strike the boiler and also resulting in the ignition of 85 the partly consumed gases thrown off by the furnace at period of low temperature.

As smoke, so called, is the result of imperfect combustion, said imperfect combustion being the result of lower furnace temperatures, and as the structures or walls aforesaid will impart heat to the gases at such periods of lower furnace temperature, it follows that the quantity of smoke issuing 90 from the stack will be diminished and also 95 that more water will be evaporated per pound of coal burned than would be the result with furnaces constructed in the usual manner. The more perfect combustion of fuel will also result in a lessened deposit of soot 100 in the boiler tubes or flues producing greater boiler economy. It will also be seen that water enters the heater at the bottom and rises through the system of pipes and is delivered into the top of the boiler and distributed through the spray pipe which is 105 above the top of the tubes or flues. As the combined area of these vertical heater tubes is much greater than the area of the feed pipe supplying them, the water will flow 110 very slowly through the heater tubes, and the water being heated by the furnace gases, the mud and other suspended matter in the water will be precipitated and sink to the bottom end of these tubes and collect in the mud drum. Therefore, when the feed water 115 heater blower is used, the mud and water will first be expelled from the heater mud drum and tubes, then the scum on the surface of the water in the main boiler will be carried away, relieving the boiler of all impurities, and increasing the life and safety of the 120 boiler by preventing the deposit of this suspended matter on the tubes and shell of the boiler. After the blowing operation is completed, feed water must be supplied promptly to the boiler.

We claim:—

1. A smoke consuming furnace comprising 130 in combination with a boiler and fire box, a

transversely curved wall of fire-resisting material extending lengthwise of and beneath the boiler and forming a heating flue for the products of combustion, and vertical baffle walls projecting alternately from the opposite side walls of the furnace partially across the space under the curved wall, and also forming supports for said curved wall.

5 2. A smoke consuming furnace comprising in combination with a boiler and fire box, two transversely curved walls of fire-resisting material, curved inversely to each other and extending lengthwise beneath and spaced from the boiler and also located above the 10 fire box and forming a heating flue for the products of combustion.

15 3. A smoke consuming furnace comprising in combination with a boiler and fire box, two transversely curved walls of fire-resisting material curved inversely to each other and extending lengthwise beneath and spaced from the boiler and also located above the fire box, and vertical baffle walls projecting alternately from the opposite side walls of 20 the furnace partially across the space beneath said curved walls.

25 4. A smoke consuming furnace comprising in combination with a boiler and fire box, a

transversely curved wall of fire-resisting material extending lengthwise beneath and 30 spaced from the boiler and also located above the fire box, and vertical baffle walls projecting alternately from the opposite side wall of the furnace partially across the space under the curved wall formed with fresh air 35 ducts therein.

5. A smoke consuming furnace comprising in combination with a boiler and fire box, side walls provided with air passages leading to the space under the grate, means for opening and closing said passages, a transversely curved wall of fire-resisting material extending lengthwise beneath and spaced from the boiler and also located above the fire box, and baffle walls projecting alternately from 40 the opposite side walls of the furnace partially across the space under the curved wall and formed with air ducts.

In testimony whereof we affix our signatures in presence of two witnesses.
